UNITED STATES PATENT OFFICE

WILLIAM C. HIERING, OF NEWARK, NEW JERSEY, ASSIGNOR TO J. E. MERGOTT COMPANY, OF NEWARK, NEW JERSEY, A CORPORATION OF DELAWARE

BAG FASTENER

Application filed November 12, 1930. Serial No. 495,100.

This invention relates to frames for ladies' handbags, and more particularly to latching devices for use on such frames.

In the usual latching devices for hand bag frames, after moving the latching device to a released position, it is then necessary to spread the frame members apart in order to obtain access to the contents of the hand bag. Inasmuch as it is necessary to frequently open ladies' hand bags, the operation of spreading the frame members apart is annoying and inconvenient.

It is an object of this invention to provide a latching device for ladies' hand bags, which device automatically spreads the frame members apart when moved to a released position.

A further object is the provision of a latching device which may be easily applied to standard shapes of hand bag frames without material alteration.

These and other advantageous objects, which will later appear, are accomplished by the simple and practical construction and arrangement of parts hereinafter described and exhibited in the accompanying drawings, forming part hereof, and in which:

Figure 1 represents a perspective view of a bag frame embodying the invention.

Figure 2 represents a side view of the latching device mounted on a bag frame.

Figure 3 represents a sectional view taken on line 3—3 of Figure 2.

Figure 4 represents a sectional view taken on line 4—4 of Figure 3.

Referring to the drawings, a pair of channelled frame members 5 and 6 are shown, hingedly connected at 7. A plate 8 is attached to member 5 by means of brads 9 passing through apertures in the frame member. The plate 8 has a slot 10 through which passes a stud 11, the portion 12 of the stud in the slot 10 being reduced in order to provide shoulders abutting the sides of the plate 8 to prevent the stud from being withdrawn without removing the plate 8 from the frame member 5.

The portion 12 of the stud has a pair of opposite grooves 13, having flat bottoms, which engage a wire spring 14 to maintain the stud in either of two positions. The

spring 14 is substantially straight as shown and rests in a recess 15 in the plate 8, (see Fig. 2), the ends of the spring passing through the frame member 5. With this arrangement, whenever the spring lies in either of the grooves 13, the tab 16, pivotally connected to the stud 11, will lie flat against the side of hand bag.

A plate 17 is secured to frame member 6 by means of brads 18, similar to the brads 9 of the plate 8. The plate 17 is provided with an aperture 19 through which passes the blunt conical nose 20 of stud 11. Adjacent the tip of nose 20, the stud 11 has a pair of opposed grooves 21, similar to grooves 13, in which a wire spring 22 rests when the stud is in either of two positions. The wire spring 22 is secured to the frame member 6 and rests in a recess 23 in the plate 17, the spring being positioned over a slot 24 in the frame member 6.

In operation, when it is desired to unlatch the frame members from the latched position as shown in Figure 3, the stud 11 is turned so that the spring 22 is out of the grooves 21 and engaging the inclined surface of the nose 20. In this position, the upward pressure of the spring 22 on the conical nose, causes a camming action on the stud 11, which results in the frame members 5 and 6 being automatically spread apart.

To latch the frame members, it is only necessary to move the tab 16 to a position where it lies flat against the side of the bag, and then press the frame members together to cause the springs 14 and 22 to snap into the grooves 13 and 21, respectively.

It is obvious that the latching device is not confined to use on channelled frame members, but may be readily mounted on various types of frame members. By means of the latching device herein described, it is not necessary to spread the frame members apart with the fingers after they have been unlatched; and access to the contents of the bag is thus facilitated.

It will also be noticed that the tab 16 either lies flat against the side of the bag or in a plane transverse to the side of the bag, the position of the tab readily indicat-

ing whether the frame members are latched or unlatched.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus disclosed my invention, what I claim as new and desire to secure by Letters Patent, is:

1. In combination with a pair of pivotally connected bag frame members, a latching device comprising plates attached to the frame members each plate having a recess, wire springs positioned in the recesses and attached to the frame members, and a stud 15 revolvably mounted in one plate and passing through the other plate, said stud having pairs of opposed slots in which the springs rest when the stud is in either of two positions, and having a conical nose, the pair 20 of opposed slots being adjacent the tip of the nose, the spring having a camming action on the nose to spread the frame members apart when the stud is rotated so that the springs are not in the slots.
2. In combination with a pair of pivotally connected bag frame members, a latching device comprising plates attached to the frame members, a stud revolvably mounted in one plate, the other plate having a recess 25 and an aperture, a spring positioned in the recess and attached to the frame member, said stud having a pair of opposed slots in which the spring rests when the stud is in predetermined positions, and a conical nose 30 on the stud having a camming action with the spring to spread the frame members when the spring is not resting in the slots.
3. In combination with a pair of pivotally connected bag frame members, a latching device comprising a plate having an aperture attached to one frame member, a second plate 45 attached to the other frame member, a stud revolvably mounted on the second plate, said stud having a conical nose passing through the apertures, and a resilient means on the first plate having a camming action on the conical nose to spread the frame members apart when the stud is rotated to an unlatching position.
4. In combination with a pair of pivotally connected frame members, a latching device comprising a plate having an aperture and attached to one frame member, a second plate 55 attached to the other frame member, a stud revolvably mounted on the second plate, said stud having a conical nose passing through the aperture, a tab pivotally mounted on the stud so as to lie either parallel or transverse to the frame members when the stud 60 is rotated, and resilient means on the first 65 plate having a camming action on the conical nose to spread the frame members apart when the tab is transverse to the frame members.

This specification signed this 15th day of April, 1931.

WILLIAM C. HIERING.
